OIL COOLER

John Ralph Holmes and John A. Winter, Lockport, and Irving M. Schultz, North Tonawanda, N. Y., assignors to General Motors Corporation, Detroit, Mich., a corporation of Delaware

Application July 2, 1941, Serial No. 400,792

4 Claims. (Cl. 257—128)

1

This invention relates to heat exchangers and, particularly, to temperature regulators for the lubricant of internal combustion engines hereinafter called "oil coolers."

To increase the efficiency of the transfer of heat between the oil and the oil temperature regulating fluid, there have been provided in oil coolers baffles to cause the oil to follow a circuitous instead of a direct path through the oil passages in the cores of the coolers. To thaw out oil congealed in the oil passages in the cores of oil coolers there have been provided in the coolers less restrictive oil passages in heat exchanging relation to the oil passages in the cores.

In the oil coolers found in the prior art the thawing out passages were generally formed as jackets which encircled or partly encircled the cores of the coolers and, consequently, only very slowly thawed out the oil in the centers of the cores and the baffles were formed as separate structural elements. This invention resides in an oil cooler in which the baffles are made to serve also as thawing out passages with the result that the thawing out passages function more efficiently because of their more advantageous location and the weight bulk and cost of the cooler is reduced.

For a better understanding of the nature and objects of this invention, reference is made to the following specification and the accompanying drawing in which is described and illustrated the preferred embodiment of the invention.

In the drawing:

Figure 1 is an end elevation with parts broken away and in section of an oil cooler and valve assembly in which is included an oil cooler in accordance with our invention.

Figures 1A and 1B are incomplete diagrammatic illustrations of the valve. Figure 1A shows the valve with parts in a position to direct the flow of oil through the warm oil path through the oil cooler. Figure 1B shows the valve with parts in a position to direct the oil through the hot oil path through the oil cooler.

Figure 2 is a side elevation of the oil cooler with parts broken away and in section.

Figure 3 is a fragmentary plan view of one of the members of which the baffles included in the oil cooler are made.

Figure 4 is an enlarged fragmentary view of the oil cooler taken as indicated by the line 4—4 of Figure 1.

Figures 5 and 6 are fragmentary sections on the same scale as Figure 4 taken as indicated by the lines 5—5 and 6—6, respectively, of Figure 3.

through one of the baffles included in the oil cooler.

The oil cooler 10 which is shown in the drawing includes a core which consists of several sections 11 made up of "hex-ended" tubes 12 disposed within a cylindrical shell 13 with their axes extending parallel to the axis of the shell. The shell 13 is, as shown in Figures 2 and 4, except at its extreme ends, encircled by a cylindrical shell 14 with inturned flanges 15 on its ends which engage and are bonded to the outer surface of the shell 13.

Between the sections of the core are disposed baffles 16. Each baffle consists of a pair of plate-like members 17 with flanges 18 on their sides and on their ends near their sides nested one within the other and bonded together to form a flat duct. The ducts defined by the baffles 16 communicate at both ends with the space between the shells 13 and 14 through slots 19 in the former. The baffles are secured to the shell 13 by means of tongues 20 which extend through the slots 19 and are bent over against and bonded to the outer surface of the shell 13. To prevent spread or collapse of the baffles 16 and also to cause the oil to swirl instead of flow smoothly through the ducts defined by the baffles there are formed on the opposed sides of the plates 17 embossments 21 which abut against and are bonded one to another. Registering openings in the plates 17 and flanges which encircle them and are nested one within the other and bonded together define passages 22 through which oil may pass from the oil passages 32 between the tubes of which one section 11 of the core is made to the oil passages between the tubes of which the next section 11 of the core is made.

To the shell 14 laterally opposite one of the outside baffles 16 there is secured a mounting pad 23. A rib 24 on the underside of the mounting pad and a baffle 25 laterally opposite the other of the outside baffles 16 bridge the space between the shells 13 and 14 and divide it into two compartments, 26 and 27, which do not intercommunicate except through the ducts defined by the baffles. Through the pad 23 there extend elongated openings 28 through which oil may enter the compartment 26 and elongated openings 29 through which oil may leave the compartment 27. Through the shell 13 laterally opposite the baffle 16 which is nearest the baffle 25 there extend openings 30 through which oil may pass from the compartment 26 into the oil passages 32 between the tubes 12 of which the core 11 is made. Through the rib 24 on the

mounting pad 23 there extend elongated openings 34 through which oil may leave the oil passages between the tubes of which the core is made.

The baffles 16, of course, extend the full length of the oil passages between the tubes 12 of which the core is made and, consequently, oil cannot pass from one section 11 of the core to another except by way of the passages 22 through the baffles. It is to be noted that the passages 22 extend through one baffle near one end and through the next baffle near the opposite end and that the openings 30 and 31 open into the sections of the core with which they communicate near the ends distant from the passage 22 through the nearest baffle.

Oil which enters the cooler 10 through the openings 28 may leave it either through the openings 29 or the openings 31. The path from the openings 28 to the openings 31, hereinafter referred to as the "hot oil path," which is indicated in Figure 1 of the drawing by the dash line arrows, is through the compartment 26, the openings 30 and the oil passages 32 between the tubes of which the core is made and the passages 22 through the baffles 16 between the sections of the core. The path from the openings 28 to the openings 29, hereinafter referred to as the "warm oil path," which is indicated in Figure 1 of the drawing by the solid line arrows, is through the compartment 26, the ducts defined by the baffles 16 and the compartment 27.

In the course of its passage through the oil passages 32 between the tubes of which the core is made on its way from the openings 28 to the openings 31 the oil is, of course, cooled by the air which passes through the tubes. The circuitous path which the baffles 16 and the location of the openings 30 and 31 and the passages 22 constrain the oil to follow on its way through the core, of course, raises the efficiency of the transfer of heat from the oil to the air. In the course of its passage through the compartment 26, the ducts defined by the baffles 16 and the compartment 27 on its way from the opening 28 to the openings 29 warm oil transfers heat to and thaws out oil congealed in the oil passages 32 between the tubes of which the core is made. The efficiency of the ducts defined by the baffles 16 in thawing out oil congealed in the oil passages 32 is, of course, increased by reason of the extension of the ducts into the interior of the core.

The oil passages 32 between the tubes 12 of which the core 11 is made are, of course, of the dimensions and form requisite to very effective extraction of heat from the oil by the air passing through the tubes 12 and, therefore, very resistive to the passage of oil when it is cold and thick. The ducts defined by the baffles are of dimensions and form effectively to transmit heat from oil traveling therethrough to oil in the oil passages 32 but less resistive to the passage of oil than the passages 32.

The oil cooler 10 was designed for use in conjunction with the valve 33 mounted on the pad 23, which is the subject of the Nemmer and O'Brien application Serial No. 396,830, filed June 6, 1941. The valve 33 includes a body 34 with an inlet port 35 and an outlet fitting 36. The oil cooler and valve assembly were designed to be installed in the lubricating system of an internal combustion engine so that oil enters the valve through the inlet port 35 and leaves it through the outlet fitting 36. The valve is so designed that when the oil is cold it passes from the inlet port

to the outlet fitting without passing through the cooler and is, consequently, warmed up as rapidly as possible; when the oil is warm it passes from the inlet port to the outlet fitting through the cooler by way of the warm oil path described above, and thaws out the oil congealed in the passages 32 between the tubes 12 of which the core 11 is made; and when the oil is hot it passes from the inlet port to the outlet fitting through the cooler by way of the hot oil path described above and is cooled by the air passing through the tubes 12. Thus the oil is brought up to its optimum temperature as promptly as possible and kept from exceeding this temperature under all conditions of operation of the engine. But, of course, other types of valves, e. g., a valve designed so that the oil passes through the cooler by way of the warm oil path when the oil is cold as well as when it is warm, may be employed with oil coolers of the type herein disclosed.

We claim:

1. In a heat exchanger, a core which includes a plurality of sections through which fluid is constrained to pass successively in heat exchanging relation to another fluid, a double walled shell which encircles the core and whose interspace is divided circumferentially into a compartment through which the second mentioned fluid may enter the heat exchanger in heat exchanging relation to the second mentioned fluid in the core and a compartment through which the second mentioned fluid may leave the heat exchanger in heat exchanging relation to the second mentioned fluid in the core, hollow members of which each opens at one end into the first mentioned compartment and at the other end into the second mentioned compartment so that the second mentioned fluid may pass through them in parallel from the first mentioned compartment to the second mentioned compartment in heat exchanging relation to the second mentioned fluid in the core extending through the core between the sections of the core, an opening through which the second mentioned fluid may enter one section 25 of the core from the first mentioned compartment without passing through the hollow members, an opening through which the second mentioned fluid may leave another section of the core, and openings through which the second mentioned fluid may pass through the hollow members from the first mentioned section of the core to the last mentioned section of the core, the mentioned openings being so disposed that the second mentioned fluid follows a circuitous instead of a direct path through the core.

2. In a heat exchanger, a core through which fluid may pass in heat exchanging relation to another fluid, hollow members through which fluid may pass in parallel in heat exchanging relation to the second mentioned fluid in the core disposed in the path of the second mentioned fluid through the core and so that they cause it to follow a circuitous instead of a direct path through the core, openings through which fluid 60 may enter the hollow members, openings through which fluid may leave the hollow members, a header into which open the first mentioned openings through which fluid may be conducted to the hollow member in heat exchanging relation 65 to the second mentioned fluid in the core, and a header into which open the second mentioned openings through which fluid may be conducted from the hollow members in heat exchanging relation to the second mentioned fluid in the core.

3. In a heat exchanger, a core which includes a

plurality of sections through which fluid is constrained to pass successively in heat exchanging relation to another fluid, a double-walled shell which encircles the core and whose interspace is divided circumferentially into a compartment through which the second mentioned fluid may enter the heat exchanger in heat exchanging relation to the second mentioned fluid in the core and a compartment through which the second mentioned fluid may leave the heat exchanger in heat exchanging relation to the second mentioned fluid in the core, hollow members of which each opens at one end into the first mentioned compartment and at the other end into the second mentioned compartment so that the second mentioned fluid may pass through them in parallel from the first mentioned compartment to the second mentioned compartment in heat exchanging relation to the second mentioned fluid in the core extending through the core between the sections of the core, an opening through which the second mentioned fluid may enter one section of the core from one of the mentioned compartments, an opening through which the second mentioned fluid may leave another section of the core, and openings through which the second mentioned fluid may pass through the hollow members from the first mentioned section of the core to the last mentioned section of the core, the mentioned openings being so disposed that the second mentioned fluid follows a circuitous instead of a direct path through the core.

4. In a heat exchanger, a core which includes a plurality of sections through which fluid is constrained to pass successively in heat exchanging relation to another fluid, a double walled shell which encircles the core and whose interspace is divided circumferentially into a compartment through which the second mentioned fluid may enter the heat exchanger in heat exchanging relation to the second mentioned fluid in the core and a compartment through which the second men-

tioned fluid may leave the heat exchanger in heat exchanging relation to the second mentioned fluid in the core, hollow members of which each opens at one end into the first mentioned compartment and at the other end into the second mentioned compartment so that the second mentioned fluid may pass through them in parallel from the first mentioned compartment into the second mentioned compartment in heat exchanging relation to the second mentioned fluid in the core extending through the core between the sections of the core and so disposed that the second mentioned fluid follows a circuitous instead of a direct path through the core, an opening through which the second mentioned fluid may enter one section of the core from one of the mentioned compartments, and an opening through which the second mentioned fluid may leave another section of the core.
